FIG. 2.

UNITED STATES PATENT OFFICE.

CHARLES A. SHEDAKER, OF PHILADELPHIA, PENNSYLVANIA.

COMBINATION-UNDERWEAR.

1,170,350.

Specification of Letters Patent.

Patented Feb. 1, 1916.

Application filed August 29, 1913. Serial No. 787,252.

To all whom it may concern:

Be it known that I, CHARLES A. SHEDAKER, a citizen of the United States, and a resident of Philadelphia, Pennsylvania, have invented certain new and useful Improvements in Combination-Underwear, of which the following is a specification.

The purpose of my invention is to provide a full opening along the side seam from the 10 waist down the leg of a closed crotch garment opened in the front at the upper end to a point above the crotch.

A further purpose of my invention is to insure additional room at the top of a side 15 opening along the thigh.

A further purpose of my invention is to reinforce the garment at the rear in proximity to the waist line and to extend the reinforcement about the edge and bottom of 20 the flap.

Further purposes of my specification will appear in the claims and specification hereof.

I have preferred to illustrate my invention by a form thereof which I have found 25 to be practical, efficient, inexpensive and convenient and which at the same time well illustrates the principles involved.

Figure 1 is a perspective view of a garment containing my invention. Fig. 2 is a 30 side elevation of the structure shown in Fig. 1 with the flap and side of the leg folded back for purposes of illustration. Fig. 3 is a section of Fig. 2 taken upon lines 3—3 35 thereof.

The upper portion 5 of my union garment is made of any convenient form, being open at 6, down to any suitable point 7 above the crotch, so that it may be put on readily. 40 I show an elastic crotch insert at 8 and short leg portions 9. From approximately the waist line, I open the side of the garment down to the bottom of the leg portion thereof, making this opening at the middle of 45 the side of the thigh and leg and securing that part of the side which is connected with the front of the garment, as at 10, with that connected with the back of the garment, as at 11, by any suitable means, as buttons 12. 50 I desire that this opening shall not extend above the waist line at its upper end and yet, with reasonable overlapping of joining side edges, shall have the effect in use of a much longer opening, giving an extent of 55 spread and conformation of opening similar to that which would be secured if the side

parts of the garment separated to a considerable height above the waist band. Without interfering with the waist band my structure gives full width of side opening 60 at the waist and a much more free spreading of the sides 10, 11 of the garment below than would otherwise be secured. I accomplish these results by the use of a flap 13 at the upper extremity of the opening, 65 buttoning it at 14, when the buttons 12 are fastened. The upper end of the side member 11 is thus free to open about the bottom 13' of the flap which may be located at any suitable point in the side of the garment, 70 preferably near the side seam. When the buttons 12 and 14 are loosened, the opening movement of the lower part of the side of the leg approximates at any given time that which it would have if the side opening were 75 extended above the waist in line with the side seam. I find that but a short length of flap 13 is required to secure the desired width of separation at the side along the 80 waist line and throughout the length of the opening. I extend the material of the reinforcement 15 about the edge 16 to cover both sides of the flap 13, passing it down into the flap bottom 13' and along the face of the fabric which the flap overlaps, as at 18, to 85 the side seam. I prefer to make the button-hole 19 in the two thicknesses of this reinforcing strip, and, in such case, not extending the fabric of the lower or drawer part of the combination garment at this point 90 farther up than sufficiently to form a seam with the lower edge of the reinforcement. It will thus be seen that the reinforcing strip is continuous about the back of the garment, 95 preferably from side seam to side seam, and about the flap. In whatever direction strain is brought along it, the strain will be transmitted to the reinforcing fabric and lengthwise of it.

Having thus described my invention, what 100 I claim as new and desire to secure by Letters Patent is:

1. A garment having an opening extending downwardly from the waist, a flap at the upper end of the opening permitting 105 greater separation of the sides of the opening at this point and a single waist band secured to the body of the garment on each side of the line of attachment of the flap and extending continuously between these 110 portions, following the contour of the outside and inside faces of the flap.

2. A union suit or garment, having one leg provided with a longitudinal opening and a rear flap to normally cover the opening when in the closed position, an approximately horizontal strip attached to the garment near the waist and to the upper end of the upper end of the rear flap and connecting the flap with the garment at a point spaced rearwardly for a substantial distance
5 from the normal longitudinal opening, with the strip folded upon itself when the flap is in the closed position whereby the upper end of the flap and the portion of the strip secured thereto may be swung rearwardly to

increase the size of the upper end of the 15 opening, and means for detachably securing the flap to the leg for retaining it in the closed position.

3. A union suit comprising a waist band extending across the back and terminating at the sides and folded intermediate its ends, and a rear piece for one leg having a portion in the form of a flap inclosed in the fold of the waistband. 26

CHARLES A. SHEDAKER.
